UNITED STATES PATENT OFFICE.

JOHN P. MUNFORD, OF BROOKLYN, NEW YORK.

SAFETY CLOTHESLINE BRACKET.

Application filed May 17, 1921. Serial No. 470,345.

To all whom it may concern:

Be it known that I, JOHN P. MUNFORD, a citizen of the United States, residing at Brooklyn, in the county of Kings and State of New York, have invented certain new and useful Improvements in Safety Clothesline Brackets; and I do hereby declare the following to be a full, clear, and exact description of the invention, such as will enable others skilled in the art to which it appertains to make and use the same.

The present invention relates to clothesline brackets, such as are used for supporting endless or movable clothes lines from windows or doors of buildings, and an object of the invention is the provision of such a device of simple and inexpensive construction, which can be readily applied to a window or door frame, and which enables the clothes line to be brought within the room for convenience in placing clothes on, or removing them from the line, without danger of the person or clothes falling, as sometimes happens when it is necessary to reach out through the window or door opening.

Another object is the provision of such a bracket for supporting the clothes line, and having novel means for holding the line when the bracket is swung out through the opening to the outside.

It is also the object of the invention to improve the device generally in its construction and detail, to enhance the utility and efficiency thereof.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a side elevation of the device showing the bracket swung into the room as when placing the clothes on or removing them from the line, the window frame or casing being shown in vertical section.

Fig. 2 is a horizontal section on the line 2—2 of Fig. 3 with the bracket on the exterior of the building.

Fig. 3 is a side elevation showing the bracket on the exterior of the building.

Fig. 4 is a fragmentary view of the win-

dow from the inside, showing the bracket in the position as seen in Figs. 2 and 3.

Fig. 5 is an enlarged section on the line 5—5 of Fig. 1 showing the line holding pin and retaining links thereof.

Fig. 6 is a perspective view of a modification.

The bracket proper includes a vertical shaft 7, a substantially horizontal arm 8 secured at one end to the shaft near the upper end of the shaft, and an inclined brace 9 secured at the lower end to the shaft near the lower end thereof and secured at its upper end to the free end portion of the arm 8. The terminals of the shaft 7 project above and below the arm 8 and brace 9, respectively, and are fitted for rotation in the bearing ears 10 projecting at an angle from plates 11 secured to one side jamb of the window frame or casing 12 at the outer side of the sashes 13, so that the brackets can be swung under the sashes, when they are raised, as seen in Fig. 1, to project into the room. The shaft 7 has a collar 14 thereon near its lower end below the brace 9, to seat on the lower ear 10, for supporting the brackets for free turning movement in the bearings.

In order to hold the bracket when swung into the room, a catch 15 is pivoted, as at 16, to said jamb of the window frame at the inner side of the window, and has hook notches 17 to engage the arm 8 and hold the bracket in place. A similar catch 18 is pivoted to the jamb at the exterior of the window frame, to engage the arm 8 when the bracket is swung to the outside, as seen in Figs. 2 and 3, to thereby hold the bracket in outstanding position and to prevent the accidental swinging thereof against the window pane.

The free end portion of the arm 8 has an eye 19 extending to one side, and a pulley 20 is carried by a hook member 21 to engage in said eye. The endless or movable clothes line 22 passes around the pulley 20 and around another pulley 23 which is supported at a distance from the building by means of a pole 24 or other support, whereby the clothes line can be made to travel to and from the building.

In order to hold the clothes line when the bracket is swung on the exterior, a pair of links or retaining arms 25 is provided, each of them having a loop 26 at one end embrac-

ing the shaft 7 and supported on a pin 27 secured through the shaft. The links or members 25 are thus loosely supported from the shaft on the pins or members 27, and said links are made from S-hooks. Said links have the loops 28 at their free ends for receiving a retaining pin or member 28 which can be readily inserted downwardly into the loops 28.

10 In using the device, after both sashes 13 are raised, and the catch 18 disengaged from the arm 8, the bracket is swung inwardly through the window opening into the room, and the catch 15 is engaged with the arm 8 to hold the bracket in place. The pin 29 is now withdrawn from the links 25, to release the clothes line 22. The clothes can then be readily pinned or pegged on the line, and the line moved for carrying clothes with 15 same to the outside. If it is desired to close the window, the two runs of the line 22 are moved between the links 25 and the pin 29 inserted. The catch 15 can now be released from the arm 8, thereby permitting the 20 bracket to be swung outwardly, as seen in Figs. 2 and 3, the pin 29 holding the line and preventing same from sagging appreciably. The lower sash can now be lowered for closing the window. After the clothes 25 have dried, the window is again opened and the bracket swung into the room as before, and the pin 29, removed for pulling the clothes into the room and removing them from the line. After the clothes are removed 30 the line 22 is again fastened between the links 25 by the pin 29, and the bracket swung to the outside and fastened by the catch 18,

By using the bracket on the interior of the building, there is no danger of the operator slipping or falling, and the clothes 40 can be conveniently fastened on and removed from the line without reaching out of the window or otherwise using more or less exertion.

Fig. 6 shows a line holding member composed of one piece or strip of metal, having a vertical yoke 26' and the angularly extending terminals or arms 25'. The arms 25' have apertures 28' to receive the line holding pin 29' and aperture 28" receiving the shaft 50 7 to pivotally mount the member on said shaft. The member is supported by a pin or member 27' secured to the shaft.

Having thus described the invention, what is claimed as new is:—

A clothes line bracket having a vertical shaft, means for supporting said shaft for turning movement, a clothes line pulley carried by the bracket, a pair of arms mounted loosely on said shaft to turn around said shaft and adapted to receive the clothes line between them, means on said shaft for supporting said arms in the desired vertical position, said arms having apertures, and a pin insertable in said apertures to retain the clothes line between said arms behind said pin.

In testimony whereof I have signed my name to this specification in the presence of two subscribing witnesses.

JOHN P. MUNFORD.
